SELF-WINDING TIMEPIECE

William Atkinson Gabriel, Elgin, Ill., assignor to
 Elgin National Watch Company, Chicago, Ill.,
 a corporation of Illinois

Application May 20, 1932, Serial No. 612,565

10 Claims. (Cl. 58—82)

This invention relates to improvements in time keeping instruments, and more particularly to improvements in self-winding timepieces. The invention further relates to self-winding watches 5 wherein the winding mechanism is actuated by the motion of the body of the wearer.

The principal object of the invention is to provide a watch wherein a reciprocating member is adapted to actuate the winding mechanism. 10 A further object of the invention is to provide a watch of the self-winding type wherein the watch movement is fixed within the case in spaced relation thereto, thus permitting the reciprocation of a weighted member within the case 15 to actuate the winding mechanism.

A further feature of the present invention is the provision of a watch assembly including a case, a watch movement and a weight-operated winding mechanism, in which the watch movement is fixed in relation to the case and is provided with manual winding means extending to the exterior of the case, and with a weight-operated self-winding mechanism having a weight located within the case and surrounding the 25 movement for normally maintaining the watch in wound condition.

The invention further provides a self-winding watch having a more evenly balanced structure than has heretofore been possible.

30 The invention still further provides a self-winding watch which is compact, reliable and whose winding mechanism is easily accessible.

These and other features of the invention will appear in the course of the following specification and claims, in which an illustrative form 35 of practicing the invention, with modifications in detail thereof, is set forth.

In these drawings:—

Figure 1 is a back plan view of a watch with 40 the back closing plate removed.

Fig. 2 is a longitudinal sectional view through the watch case, substantially on line 2—2 of Fig. 1, showing the weight in elevation.

Fig. 3 is a longitudinal sectional view substantially on line 3—3 of Fig. 4.

Fig. 4 is a longitudinal sectional view substantially on line 4—4 of Fig. 3, but showing the watch movement in elevation.

Fig. 5 is a transverse sectional view substantially on line 5—5 of Fig. 3.

Fig. 6 is an enlarged fragmentary transverse sectional view substantially on line 6—6 of Fig. 3.

Fig. 7 is a fragmentary transverse sectional view, showing a modified arrangement for guiding the weight in the casing.

Fig. 8 is a back view of the same, with a portion broken away for clearness.

Fig. 9 is a longitudinal section of the same.

Fig. 10 is a perspective view of the modified form of weight.

Briefly, as shown in the drawings, the present invention provides a self-winding wrist watch or the like wherein a watch movement is fixedly mounted within the watch case in spaced relation thereto, whereby a weighted member, which is likewise mounted within said case by means of suitable anti-friction devices is caused to shift therein by any motion of that part of the body of the wearer to which the watch is secured. In addition to the ordinary manual winding and setting means, there are provided additional winding gears to which the said weighted member is operatively connected in such a manner that its reciprocation within the case will actuate the gears and thus wind the watch. In addition to the anti-friction devices which support the weighted member and permit its ready reciprocation, there are provided means to absorb the shocks incident to the reciprocation of said weighted member.

In Figures 1 to 6 the watch case comprises a body 10 which is provided with integral end and side walls in the usual manner. The said body 10 has a back closing plate 11 and a bezel 12 which are secured thereto by the usual snap ribs 13 and 14 respectively. The bezel 12 has secured thereto a watch crystal 15. The body 10 of the watch case has flanges 16 extending toward the center of the said watch case. The said flanges have supporting portions 17 in spaced relation to the corresponding end walls of the body of the watch case proper. A watch movement 18 having rib portions 19 is mounted between the supporting portions 16 in such a manner that the said rib portions rest upon the ends of the said supporting portions and the free edge of the bezel 12 presses upon said movement whereby the watch movement is fixedly mounted within the case. Other suitable fastening devices may be used to more firmly secure the said watch movement if desired. The watch movement is provided with the usual hand winding and setting stem 20 which extends through a side wall of the casing and has secured thereto the usual crown 20a. The watch movement is provided with a dial face 21 and a hand pivot 22 which extends through the center of said face. The watch case is provided with grooves 23 which serve as guide or track ways for the actuating member to be hereinafter described.

The actuating member 24 has an opening 25 therein whereby it fits loosely around the centrally fixed watch movement 18 and is free to reciprocate lengthwise of the watch case. The member 24 is provided with recesses 26 in which the anti-friction or guide rollers 27 are rotatably secured by screws or pins 28. The manual winding stem 20 of the watch movement extends through a slot 29 in the member 24, said slot permitting the reciprocation of said member within the case without interference from the winding stem. The ends of the member 24 are provided with grooves 30 in each end of which is a cavity 31 to receive the end 32 of a cushion spring 33 whereby said spring is held in said member 24. The cushion springs serve as a means to absorb any vibration or shock incident to the reciprocation of said member 24 within the case.

20 The member 24 is supported in the watch case body 10 by the rollers 27 which travel in the grooves 23 which are provided in the sides of the said body 10. There is sufficient distance between the supporting portions 17 of the flanges 25 16 and the walls of the watch case to permit reciprocation of the member 24.

The self-winding mechanism will now be briefly described, reference being had particularly to Figures 1, 3 and 6. The movement 18 includes a main spring (not shown) and a barrel winding arbor 34 for the same. As shown in Fig. 6, the movement includes a main bridge plate 35, in which one end of the arbor 34 is journaled, and an auxiliary bridge plate 36 secured in spaced relation therefrom by screws 37 or the like (Figures 1 and 3). A stud 38 is fixedly secured to the winding arbor 34 and is journaled at its free end in the auxiliary bridge plate 36, and rotatably supports between the bridge plates 35 and 36 a bushing 39 to which is fixedly secured a ratchet 40 and a gear 41. The winding arbor 34 has a gear 42 secured thereto. The ends of a pin 43 are journaled in the bridge plates 35 and 36. Secured to said pin 43 is a pinion gear 44 which meshes with the gear 42. Likewise secured to said pinion gear is a gear member 45 which meshes with the gear 41. The ends of another pin 46 are journaled in the bridge plates. This pin 46 serves as a fulcrum for a U-shaped lever 47 having a forked end 48.

50 A driving pawl 49, having a hooked end 50 to engage the ratchet 40, is secured to the lever 47 by a pivot pin 51 and is held in constant engagement with said ratchet by a spring 52 secured to the lever 47 by a screw 53. A retaining pawl 54, secured to the bridge plate 36 by a screw or the like as at 57, is normally held in contact with the ratchet 40 by a spring 55. The forked end 48 of the lever 47 is engaged by a pin 56 on the member 24 whereby the winding mechanism is actuated.

Having described the preferred embodiment of the invention, the operation will now be briefly described. When the watch is worn on the wrist of a person, any movement of the wrist or arm will cause the member 24, which is supported by the rollers 27 travelling in grooves 23 located in the watch case 10, to reciprocate within the case by the action of gravity or by inertia. The pin 56 moving with the member 24 will cause the lever 47 to move in a clockwise direction when said member moves in the direction indicated by the arrow A in Figure 3. This movement of the lever causes the driving pawl 49 to rotate the ratchet 40 in a clockwise direction. This slight

rotation of the ratchet will cause rotation of the gear 41 which meshes with a gear member 45. Thus the rotation is imparted through the gear member 45 to the pinion gear 44 which drives the main gear 42 to which the winding arbor 34 is fixedly secured.

When the member 24 moves in the opposite direction to that indicated by the arrow A in Figure 3, the pin 56 causes a counterclockwise movement of the lever 47 about its pivot 46 and the pawl 49 is moved freely over the teeth of the ratchet 40 which is held in position by the retaining pawl 54.

The cushion springs 33 act as shock absorbers to prevent undue strain and vibration when the member 24 reaches the limit of its movement in either direction. It was previously pointed out that the watch may be manually wound and set by the usual stem 20 having the crown 20a secured thereto.

20

Figures 7 to 10 show slight modifications of the various parts of the watch. Figure 10 shows a slightly modified form of the member 24. In this case the member 24a has recesses 26a in which are mounted the rollers 27a near the upper face thereof. Figures 7, 8 and 9 show the grooves 23a near the top of the case instead of being centrally located between the bezel and closing plate as in Figures 1 to 6.

25

It is obvious that minor changes in the details of construction and arrangement of the parts may be made without departing from the spirit of the invention as set forth in the appended claims.

30

Having thus fully described my invention, what I claim as new and desire to secure by Letters Patent, is:—

35

1. In a self-winding timepiece, a case, an apertured member mounted for reciprocation within said case, a watch movement fixedly mounted on the case and disposed within the aperture in said member, the dimensions of said watch movement being less than the dimensions of the aperture in said member, a cut-out portion in the side of said member, a manual winding stem extending through said cut-out portion whereby to permit the reciprocation of said member, and means operated upon the reciprocation of said member for automatically winding the watch.

40

2. In a self-winding timepiece, a case, an apertured member mounted for reciprocation within said case, a watch movement fixedly mounted on the case and disposed within the aperture in said member, the dimensions of said watch movement being less than the dimensions of the aperture in said member, a cut-out portion in the side of said member, a manual winding stem extending through said cut-out portion whereby to permit the reciprocation of said member, and means including an arcuate shaped lever pivoted at one end thereof and loosely engaged at the other end thereof with said member for automatically winding the watch upon the reciprocation of said member.

45

3. In a self-winding timepiece, a case, a watch movement fixedly mounted within said case in spaced relation thereto, a weighted member having end portions connected by leg portions and adapted to reciprocate within said case, a manual winding stem extending from said watch movement through said case, a portion of said weighted member being cut away to permit the reciprocation thereof without interference from said winding stem, spaced bridge plates mounted on said watch movement, a gear train positioned between

50

55

60

65

70

75

75

said plates, and means for actuating said gear train upon reciprocation of said weighted member to automatically wind the watch.

4. In a self-winding timepiece, a case, a watch movement fixedly mounted therein, a reciprocating member mounted within said case, a bridge plate secured to said watch movement, an additional plate secured in spaced relation to said bridge plate, a gear train between said plates, and means including a lever pivotally mounted between said plates and having the free end thereof loosely connected to said reciprocating member for actuating said gear train upon reciprocation of said member to wind the watch.

5. In a self-winding timepiece, a case having upstanding ledges in spaced relation to the ends of the case whereby to provide end chambers, a watch movement mounted on said ledges in spaced relation to said case, a member mounted for reciprocation within said case and having the ends thereof disposed within the end chambers in said case, a gear train mounted on said watch movement, means for actuating said gear train upon reciprocation of said member to wind the watch, and a cushioning member carried at each end of said reciprocating member to engage the case at the extremities of the movement of said member.

6. In a self-winding timepiece, a case, an apertured member mounted for reciprocation within said case and having a slot extending through a side wall thereof, a watch movement fixedly mounted within said case and disposed within the aperture in said member, the dimensions of said watch movement being less than the dimensions of said aperture in said member whereby to permit the free reciprocation thereof, a manual winding stem extending through said slot in said member, and means including a train of gears for automatically winding the watch upon reciprocation of said member.

7. In a self-winding timepiece, a case having a plurality of spaced grooves forming track ways, a watch movement fixedly mounted within said case in spaced relation thereto, a member having a plurality of spaced recesses coinciding substantially with the grooves in said case, a rotatable wheel mounted in each of the recesses in said member in fixed relation thereto, each of said wheels being adapted to travel in a corresponding groove in said case whereby to permit reciprocation of said member, and means con-

necting said member with said movement for automatically winding the timepiece upon reciprocation of said member.

8. In a self-winding timepiece, a case, a watch movement fixedly mounted within said case, a member mounted for reciprocating movement within said case, spaced bridge plates mounted on said movement, a winding mechanism mounted between said bridge plates and including a winding gear, a stop pawl pivotally mounted between said bridge plates and adapted to yieldingly engage said gear, a lever having one end thereof pivotally mounted on one of said bridge plates and having the opposite end thereof connected to said reciprocating member, and a driving pawl pivotally mounted on said lever and adapted to yieldingly engage said gear whereby to drive the same upon reciprocation of said member.

9. In a self-winding timepiece, a case, a watch movement including the usual manual winding and setting stem, means for fixedly mounting said watch movement in spaced relation to said case, a weight member, means for mounting said member within said case for reciprocating movement relative thereto, a winding mechanism connected to said watch movement, a lever having one end thereof fixedly pivoted adjacent one side of said weight member and stationary with respect to the movement thereof and having the other end thereof loosely engaged with said weight member at the opposite side thereof and movable therewith, and means associated with said lever for automatically actuating said winding mechanism upon movement of said member relative to said watch movement.

10. In a self-winding timepiece, a case, a movement secured in spaced relation to said case and including a manual winding and setting stem, a weight member mounted for reciprocation within said case, bridge plates overlying one another and secured in spaced relation to each other, a winding train between said bridge plates, a lever having one end thereof fixedly pivoted independently of said weight member adjacent one side thereof and having the other end thereof loosely engaged with said weight member at the opposite side thereof and movable therewith, and means associated with said lever for automatically actuating said winding train upon reciprocation of said weight member.

WILLIAM ATKINSON GABRIEL.
